UNITED STATES PATENT OFFICE.

RUSS J. CHRISTY, OF FREMONT, OHIO.

DESIGN FOR A BODY FOR MAYONNAISE-MIXERS.

SPECIFICATION forming part of Design No. 32,758, dated May 29, 1900.

Application filed May 9, 1898. Serial No. 680,230. Term of patent 7 years.

To all whom it may concern:

Be it known that I, RUSS J. CHRISTY, residing at Fremont, in the county of Sandusky and State of Ohio, have invented and produced a new and original Design for the Body of a Mayonnaise-Mixer, of which the following is a specification, reference being had therein to the accompanying drawing.

This invention consists in a design for a mayonnaise-mixer, in which an ornamental appearance is produced by the form of parts and by the contrast of colors of material of which the article is composed.

The drawing is a perspective view showing the design for a mayonnaise-mixer.

The standard A is of metal, tinned or nickel-plated to present a bright surface, and is of the form shown in the drawing. The bright metallic band B surrounds the bowl C, which bowl is of white earthenware, of porcelain, of the form shown, having a white flange c above the band B. The arm D, of the form shown,

projects at a right angle from the standard A.

The feed-cup H has a cylindrical body and a conical lower portion h, terminating in a spout I above the bowl C. The feed-cup is of bright metal and has the raised band II around its outer surface and above the band a of the standard.

The characteristic features of the design are the ornamental form and arrangement of the parts and the contrast of colors of the materials, producing a new and ornamental design for a body of the mayonnaise-mixer.

What I claim is—

The design for the body of a mayonnaise-mixer, as herein shown and described.

In testimony whereof I affix my signature in presence of two witnesses.

RUSS J. CHRISTY.
